SPEED RESPONSIVE SIGNALING
MECHANISM

Frank N. Bailey and Raymond P. Humpal, Rockford, Ill., assignors to Woodward Governor Company, Rockford, Ill., a corporation of Illinois

Application June 8, 1950, Serial No. 166,872

8 Claims. (Cl. 177—311.5)

1

This invention relates to a mechanism for actuating a signalling device such as a switch when a rotating part reaches a predetermined speed.

One object is to provide a latch mechanism of novel and simple construction normally holding the signalling device in one position and releasable by a rotating flyweight to permit movement of the device to another position to give the signal.

Another object is to reset the latch mechanism in a novel manner.

The invention also resides in the novel construction and arrangement of the latch which enables a plurality thereof to be arranged compactly and operated at different speeds and to be reset by a common actuator.

Other objects and advantages of the invention will become apparent from the following detailed description taken in connection with the accompanying drawings, in which

Figure 1 is a longitudinal sectional view of a signalling device embodying the novel features of the present invention.

Fig. 2 is a sectional view taken along the line 2—2 of Fig. 1.

Fig. 3 is a fragmentary enlarged view similar to Fig. 2 showing the parts in different positions.

Fig. 4 is a view of a part of Fig. 1 showing the parts in a different position.

Fig. 5 is a perspective view of the switch actuating arm.

Fig. 6 is a perspective view of the flyweights.

In the drawings, the invention is shown for purposes of illustration embodied in a mechanism adapted to actuate a signalling device such as a self-contained precision snap switch 10 when a rotary part such as a shaft 11 reaches a predetermined speed. The shaft is journaled in spaced antifriction bearings 12 which are supported in the outer end portion of a support in the form of a casting 13 having a flange 14 fitting into and secured to the open end of a cup-shaped casing 15 by which the switch and its actuating mechanism are enclosed. Where a plurality of signals are to be given at different speeds, a corresponding number of additional switches 10' are spaced around the support 13 with the casings thereof secured to the support by screws 16. The actuating pins 17 of the switches project outwardly along radii of the shaft 11.

The switch pins 17 are actuated by inward and outward swinging movements of individual elongated and substantially straight arms 18 fulcrumed on tangentially disposed pins 19 which

2

are angularly spaced around the support 13 at the inner end of the casing 15. About midway between its ends, each arm 18 bears against the associated switch pin 17 and is urged outwardly by a compression spring 20 seated in the casting 13. The outward movement of each arm is limited by engagement of its free end with the interior of the casing 15 (see Fig. 4).

In accordance with the present invention, each of the arms 18 is held inwardly in one switch actuating position (Fig. 1) by a latch 21 which is mounted in a novel manner so as to be tripped and released from its keeper 22 when the latch is struck by a flyweight 23 as the shaft 11 attains a speed predetermined by the loading of the flyweight. Herein, the latch is L-shaped with its longer leg pivoted on a pin 24 which projects into the outer end of the arm 18 longitudinally thereof and is supported thereby on opposite sides of the latch. The outer end of the pin is guided in a radial slot 25 in an L-shaped member 26 secured against the inner side of the flange 14 of the supporting casting 13. The latch is thus supported by the arm 18 for bodily radial movement and by the pin 24 for swinging of its short leg 27 in a direction generally circumferentially of the shaft 11. It is urged in a direction reverse to the shaft rotation by a torsion spring 28 encircling the pin 24 adjacent the latch.

The latch keeper 22 comprises a straight bar of rectangular cross section forming one leg of the L-shaped member 26 above referred to which is secured to the flange 14 to position the keeper along the inner side of the latch supporting pin 24. The widths of the latch and keeper surfaces 29 and 30 are correlated with the range of movement of the switch arm 18 so that when the latch is tripped and the arm 18 is swung outwardly, the end 29 of the latch will bear against the flat face 30 of the keeper as shown in Fig. 3. Then, when the arm is moved inwardly and the latch leg 27 passes the inner face 31 of the keeper, the latch will be swung into set position as shown in phantom in Fig. 3 by the spring 28.

The flyweights 23 for tripping the respective latches 21 are mounted on a ballhead 32 on the inner end of the shaft 11. Each comprises a block of metal pivoted near one end on a pin 33 mounted on the ballhead for swinging of the flyweight in a radial plane which includes the inner end 29 of the latch. A spring 34 which urges the flyweight inwardly acts in compression between an adjustable cup 35 and the head of a plunger 36 which bears against a seat 37 in the flyweight on the side of the pivot pin 33.

opposite the flyweight proper. The cup 35 is threaded into a hole in the ballhead so as to be adjusted axially to vary the loading of the flyweight and therefore the speed at which a projection 38 on the latter will strike the latch surface 29 as the ballhead accelerates. By making the scale of the flyweight substantially higher than that of the spring 34, the flyweight may be rendered unstable and its outward movement to trip the latch may be made to occur quickly and with somewhat of a snap action. The flyweights for tripping the latches of the four switches 10 and 10' are arranged in pairs on opposite sides of the ballhead with their projections 38 disposed in the planes of the respective latches 21. 15

With the latches constructed and arranged as above described, all of them may be reset by movement of a single member mounted on the support 13 within the latch arms 18 and movable axially of the shaft 11. The resetting member comprises a spider 39 secured to one end of a plunger 40 which is slideable in bearings 41 on the support 13 and urged into the retracted position shown in Fig. 1 by a compression spring 42 acting on a shoulder 43 on the plunger. The arms of the spider are formed with inclined cam surfaces 44 coaxing with follower rollers 45 which are mounted in yokes 46 secured to and projecting inwardly from the latch supporting arms 18 adjacent the latches. When the plunger 40 is shifted axially and to the right as viewed in Fig. 1, the cams 44 will engage the rollers 45 of all of the released latch arms and cam the latter inwardly far enough for the latch ends 29 to pass and hook around the keepers 22. All of the latches are thus reset simultaneously.

While the reset plunger may be actuated by various means, a solenoid 47 is employed in the present instance with its core 48 secured to the supporting casing 13 and spaced axially from the ballhead 32. The armature 49 of the solenoid is slideable in the core and bears against the outer end of the plunger 40 which therefore executes its resetting movement whenever the solenoid coil is energized.

In service use of the device above described, the individual springs 34 will be adjusted to load the flyweights differently for response of the corresponding switches to different predetermined speeds of the shaft 11. With all of the latches reset as shown in Fig. 1, each flyweight swings outwardly in proportion to the speed of the shaft 11 and passes its associated latch end 29 until the shaft attains a speed sufficient to bring the flyweight projection 38 to a radius equal to that of the latch end 29. In the next revolution of the shaft 11, the edge of the flyweight projection 38 will strike the latch end 29 and the momentum of the advancing flyweight will swing the latch to carry its end portion 27 along the keeper surface 31 in the direction of rotation of the shaft. As the latch end passes the keeper surface 31, the latch and its supporting arm 18 are free to move outwardly under the action of the spring 20 thus changing the condition of the associated switch 10, the latch then being positioned as shown in full in Fig. 3. The latches of the other switches are tripped in a similar manner when they are struck by their corresponding flyweights.

In the limit outward positions of the latch supporting arms 18, the latches remain in engagement with the keeper surface 30 as shown in Figs. 3 and 4, and the follower rollers 45 are positioned for proper engagement with the cam sur-

faces 44 when the solenoid is actuated to shift the resetting spider 39. In this movement all of the released arms 18 are cammed inwardly far enough to permit engagement of their latches with the keepers 22.

We claim as our invention:

1. Speed responsive signalling mechanism having, in combination, a rotatable support, a plurality of flyweights spaced annularly around and longitudinally of the axis of rotation of said support and pivoted on the latter to move outwardly as the speed of the support increases, a plurality of annularly spaced arms one for each of said flyweights extending longitudinally of said axis and each swingable transversely of the latter and into and out of an inactive position, means normally urging each of said arms away from its inactive position, a plurality of latches one pivoted on and projecting from each arm and engageable with each of said flyweights, each latch being engageable by its flyweight at a predetermined speed of said support but disposed out of the path of the flyweight at all other speeds, a keeper for each latch engageable with the latter to hold its arm in said inactive position thereof but disengageable from the latch when the latter is struck by its flyweight, a device for giving a signal in response to movement of each of said arms out of said position thereof, a resetting member movable along said axis into and out of a normally inactive position, and means operable in response to movement of said member out of said inactive position thereof to move each of said arms into its inactive position and each of said latches into holding engagement with its keeper.

2. A speed responsive signalling device having, in combination, a rotatable support, a flyweight pivoted on said support and movable outwardly therefrom as the speed of the support increases, a latch, a member supporting said latch for movement toward and away from said axis into and out of a set position in which the latch is disposed at a predetermined radius from the axis, means normally urging said latch and said member away from said set position, a stationary keeper engageable with said latch to hold the latter in said set position but disengageable from the latch when the latter is struck by said flyweight, a device for giving a signal in response to movement of said latch and said member out of said set position, a part on said flyweight disposed at said predetermined radius and engaging said latch to release the latter from said keeper at a predetermined speed of said support, means providing a surface engageable with said latch in all of its positions so as to guide the latch into and out of said set position, a resetting element movable into and out of a normally inactive position, and means engageable with said latch supporting member and actuated by movement of said resetting element out of said inactive position to move said latch along said guide surface toward and into said set position.

3. Speed responsive signalling mechanism having, in combination, a rotatable support, a plurality of flyweights spaced annularly around and longitudinally of the axis of rotation of said support and pivoted on the latter to move outwardly as the speed of the support increases, a plurality of annularly spaced arms one for each of said flyweights extending longitudinally of said axis and each swingable transversely of said axis and into and out of an inactive position, means

normally urging each of said arms away from its inactive position, a plurality of latches one pivoted on and projecting from each arm and engageable with its flyweight at a predetermined speed of said support but disposed out of the path of the flyweight at all other speeds, a keeper for each latch engageable with the latter to hold its arm in said inactive position thereof but disengageable from the latch when the latter is struck by its flyweight, and means responsive to the movement of each arm away from said inactive position thereof and operable in such movement to give a signal.

4. Speed responsive signalling mechanism having, in combination, a rotatable support, a flyweight pivoted on said support and movable outwardly as the speed of said support increases, a member movable toward and from the axis of said support and into and out of a set position, means normally urging said member away from said set position, a latch pivoted on said member to swing about an axis parallel to that of said rotatable support and projecting toward said axis for engagement with said flyweight at a predetermined speed of said support, said latch being disposed out of the path of the flyweight at other speeds, a keeper for said latch engageable with the latter to hold said member in set position but disengageable from the latch when the latter is struck by said flyweight, a device for giving a signal in response to movement of said member out of said set position, and surfaces on said latch and said keeper interengageable to guide the latch into holding engagement with the keeper.

5. A speed responsive signalling device having, in combination, a rotary support, a flyweight rotatable with said support and mounted thereon to move transversely of the axis of said support in response to changes in the speed of the latter, a member mounted for movement toward and away from said axis to and from a set position, a stationary latch keeper, a latch for engaging said keeper to hold said member in said set position, means mounting said latch on said movable member for bodily movement therewith and also for movement relative to the member into and out of engagement with said keeper along a path which intersects the circle of revolution of said flyweight when the latter is turning at a predetermined speed whereby to permit disengagement of the latch and flyweight after the latch has been struck by the flyweight at said predetermined speed and moved in unison with the latter along said path and out of engagement with said keeper, a device for giving a signal in response to movement of said member away from said set position following disengagement of said latch from said keeper, an element axially spaced from said support and mounted for movement longitudinally of the rotational axis of the latter between an active and a normal inactive position, and means actuated by said element in moving to said active position and engageable with said member to move the latter and reset said latch.

6. A speed responsive signalling device having, in combination, a rotary support, a flyweight rotatable with said support and mounted thereon to move transversely of the axis of said support in response to changes in the speed of the latter, a member mounted for movement toward and away from said axis to and from a set position, a

stationary latch keeper, a latch for engaging said keeper to hold said member in said set position, means mounting said latch on said movable member for bodily movement therewith and also for movement relative to the member into and out of engagement with said keeper along a path which intersects the circle of revolution of said flyweight when the latter is turning at a predetermined speed, said path diverging away from said circle whereby to permit disengagement of the latch and flyweight after the latch has been struck by the flyweight at said predetermined speed and moved in unison with the latter along said path and out of engagement with said keeper, and a device for giving a signal in response to movement of said member away from said set position following disengagement of said latch from said keeper.

7. A speed responsive signalling device having, in combination, a rotary support, a flyweight rotatable with said support and mounted thereon to move transversely of the axis of said support in response to changes in the speed of the latter, a member mounted for movement toward and away from said axis to and from a set position, a stationary latch keeper, a latch for engaging said keeper to hold said member in said set position, means pivotally mounting said latch on said movable member to swing about an axis parallel to the axis of said support and into and out of engagement with said keeper along a path which intersects the circle of revolution of said flyweight when the latter is turning at a predetermined speed, said latch path diverging away from said circle whereby to permit disengagement of the latch and flyweight after the latch has been struck by the flyweight at said predetermined speed and moved in unison with the latter along said path and out of engagement with said keeper, and a device for giving a signal in response to movement of said member away from said set position following disengagement of said latch from said keeper.

8. A speed responsive signalling device having, in combination, a rotary support, a member mounted for movement toward and away from the axis of said support to and from a set position, a flyweight pivotally mounted on said support to swing about an axis parallel to said support axis in response to changes in speed of said support, a latch pivotally mounted on said member to swing about an axis also parallel to said support axis and projecting toward said flyweight to be struck thereby at a predetermined speed of said support, a stationary keeper engaged by said latch to hold said member in said set position, said latch disengaging said keeper when struck by said flyweight, and a device for giving a signal in response to movement of said member away from said set position following disengagement of said latch from said keeper.
